CHILD'S CRAYON AND SCISSORS HOLDER

Walter S. Gass, Seward, Nebr.

Application February 8, 1949, Serial No. 751

Term of patent 14 years

(Cl. D58—11)

To all whom it may concern:

Be it known that I, Walter S. Gass, a citizen of the United States, residing at Seward, in the county of Seward and State of Nebraska, have invented a new, original, and ornamental Design for a Child's Crayon and Scissors Holder, of which the following is a specification, reference being made to the accompanying drawing, forming a part hereof.

In the drawing:

Fig. 1 is a side elevational view of a child's crayon and scissors holder, showing my new design;

Fig. 2 is a plan view; and

Fig. 3 is a front end view thereof.

The dotted line showings of crayons and scissors are for illustrative purposes only.

I claim:

The ornamental design for a child's crayon and scissors holder, substantially as shown and described.

WALTER S. GASS.
